Carpets

DESIGN.

—o—

A. L. HALLIDAY.

CARPET.

No. 17,769.

Patented Oct. 11, 1887.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,769, dated October 11, 1887.

Application filed September 8, 1887. Serial No. 249,184. Term of patent 3½ years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a body portion, A, and a border portion, B.

The body part A of my design consists of a prominent curving stem-work inclosing or 20 supporting within its curves irregular and varied leaf and flower forms. The ends and branches of the stem curve around, terminating in spiral or scroll shapes. Here and there upon or within the stem-work are large leaves

or flowers grouped with smaller figures. Between the prominent figures are less prominent open-work figures of irregular outline.

The border B has a similar curving stem-work, two stenus starting from a central point and curving in opposite directions. Small 30 leaves and flowers are clustered around the central point from which the stems project, and in the angles formed by the spreading stems large leaves are placed. Smaller figures are attached to the stem at different points.

What I claim as new, and desire to secure by Letters Patent, is—

1. In a design for carpets, the body A, substantially as shown.
2. In a design for carpets, the border B, substantially as shown.
3. The design for carpets, consisting of the body A and border B, substantially as shown.

ARTHUR L. HALLIDAY.
